ROOF CONSTRUCTION

John Muhr, Dayton, Ohio
(650 SW. 62nd Court, Miami, Fla.)

Filed Aug. 24, 1956, Ser. No. 606,112

1 Claim. (Cl. 50—64)

This invention relates to a roof construction and more particularly to a roof construction embodying pre-cast roof tiles adapted to attach directly to the rafters and purlins of a roof structure, although not necessarily so limited.

One object of this invention is to provide a tile roof construction which may be economically and rapidly assembled upon a substructure of rafters and purlins without sacrifice in the weather resistance and appearance of the finished roof.

Another object of this invention is to provide a roof construction embodying a novel roof tile design, the roof tile being attachable directly to the rafters and purlins of the roof substructure, without the use of intermediate roof boards.

A further object of this invention is to provide a roof structure which depending upon the pitch of the roof structure, is water-tight for average weather conditions without supplementary sealing means and which may include a vent opening for ventilating the air space under the roof tile when employed in tropical climates.

Other objects and advantages reside in the construction of parts, the combination thereof, the method of manufacture, and the mode of operation, as will become more apparent from the following description.

In the drawing,

Figure 1 is an elevational view of a gable roof embodying the present invention, where in overlapping tiles of a substantially rectangular shape are applied to the rafters and purlins of a roof substructure.

Figure 2 is an enlarged sectional view taken substantially along the line 2—2 of Figure 1.

Figure 3 is a plan view of the under side of a roof structure, embodying the present invention, wherein tiles of substantially square shape are attached to the rafters and purlins of the roof structure.

Figure 4 is a perspective view of a roof tile of this invention, illustrating the under side of the tile of Figure 3.

Figure 5 is a perspective view of a roof tile of this invention, illustrating the top side of the roof tile of Figure 3.

Referring to the drawing in detail, the roof structure comprises a plurality of equispaced, parallel, inclined rafters 10 extending oppositely from a ridgepole 12, as shown in Figure 2. Extending parallel to the ridgepole 12 are a plurality of equispaced purlins 14 secured in spaced relation to the rafters 12.

In the preferred construction, the rafters are notched at equispaced intervals along the top surface thereof to a depth equal to one-half the depth of the purlins for receipt of the purlins. The purlins are notched correspondingly along the lower surface thereof at equispaced intervals to a depth equal to one-half the depth of the purlins. In assembling the rafters and purlins, the notches in the purlins are brought into interlocking engagement with the notches in the rafters.

It is to be noted that the rafters 10 are notched upon

2

the upper surface thereof which is subject to longitudinal compression forces. Since these notches are filled by the purlins, however, weakening of the rafters is not to be expected. In the construction outlined above, the rafters may be 2" x 6" in cross-section, with purlins being 2" x 4" in cross-section.

In Figure 3 of the drawing the intersecting rafters and purlins are illustrated as forming a rectangular lattice with the purlins being spaced apart a distance equal to twice the spacing between the rafters. The invention, as will be apparent from the following description, is not limited to such a configuration, however.

Roof tiles 16 illustrated in Figures 4 and 5, are adapted to be secured to the lattice formed by the purlins and rafters. Each roof tile 16 is provided with four spaced right angular flanges 18 projecting from the under side of the tile. These flanges are cast with the tiles, which may be a concrete aggregate, clay, a plastic, a glass, or any suitable ceramic material, or the like.

The flanges 18 cooperate to form two intersecting channels in the nature of an open cross on the under side of the tile such that the flanges may straddle a rafter passing under the tile from side to side or they may straddle a purlin passing under the tile from end to end.

The roof tile 16 is placed directly on the lattice formed by the rafters and purlins in staggered tiers, as clearly illustrated in Figure 1, there being tiles 16 engaging each rafter 10 at points midway between each pair of adjacent purlins 14, and tiles 16 engaging each purlin 14 at points midway between each pair of adjacent rafters 10.

As shown in Figures 3, 4 and 5 the tiles 16 present a substantially square surface area. Tiles 16a, shown in Figure 1, are modified, in that they present a substantially rectangular surface area illustrating that the roof construction described herein is not limited to the use of tiles of a square configuration.

Each tile 16, or 16a is provided with a rib 20 at one end thereof and a hollow arched portion 22 at the opposite end. As clearly shown in Figure 1, adjacent tiles in horizontal tiers overlap, the rib portion 20 of one tile projecting under and mating with the arched portion 22 of the adjacent tile.

Adjacent horizontal tiers of the tiles are staggered in overlapping relation. Each tile 16, or 16a, has a raised lower side 26, adapted to project over the upper side of the tiles in the adjacent lower horizontal tier. Each tile 16, or 16a, is further provided with an arch 23 centrally located in the raised lower side thereof, adapted to project over the arched portions 22 of the tiles of the adjacent lower tier.

Dimensionally, the lattice formed by the rafters and purlins may take any regular rectangular configuration. The tiles 16 must be proportioned accordingly, such that each tile has a length, along the tier slightly greater than the distance between rafters, and a width across the tier slightly greater than one-half the distance between adjacent purlins.

The tiles 16, or 16a, are secured to the lattice by suitable nails or pins as indicated at 30 driven transversely through the rafters or purlins and through the flanges 18 of the tiles. Suitable holes 31 are provided in the flanges 18 prior to the assembly of the tiles. Thus, once the rafters and purlins have been assembled to provide the rectangular lattice, the tiles are readily assembled by laying the tiles lowermost tier first, securing each tile with one or more nails 30. The resultant roof covering is structurally sound without the use of any intermediate roofing or the like between the tile and the lattice. It is to be noted that each tile engaging a purlin has sides abutting the rafters, as illustrated in Figure 3. Therefore, these tiles cannot twist or pivot upon the

purlins, with the result that the tiles engaging the rafters and overlapping with the tiles engaging the purlins are stabilized and cannot twist or pivot upon the rafters. Clearly, such construction effects a considerable reduction in material costs, by eliminating the need for roof boards providing a flooring immediately under the roof tiles.

The roof structure illustrated in the drawing may be employed on both gabled roofs and pitched flat roofs. When the tiles are to be applied to a gable roof a ridge tile 32 adapted to straddle the ridgepole 12 is provided. Each ridge tile 32 comprises an angular cover portion 34 and a pair of spaced parallel flanges 36 projecting downwardly therefrom. As illustrated, the cover portion 34 and the flanges 36 comprise an integral tile. The flanges 36 are spaced to engage the ridgepole 12 between adjacent rafters 10 and are secured to the ridgepole by suitable transversely driven nails or pins. The ridge tiles 32 are each provided with a rib 38 on one end and an arched portion 40 on the opposite end, such that the ridge tiles may be secured to the ridgepole 12 in overlapping relation.

For tropical climates the oppositely directed sides of the angular cover portion 34 may extend in spaced parallel relation above the roof tiles 16, or 16a, in the main body of the gable roof, so as to provide for ventilation under the roof tiles. For such construction, the angle between the side of the angular covering portion 34 must complement the pitch of the roof. Ventilation in such a manner is preferred in tropical climates for the reason that hot gasses in an air space under the tiles will rise naturally to the vent adjacent the roof tile. To minimize water leakage under the ridge tile 32 during rain storms, an upwardly directed flange 42 is provided at the top of the tiles adjacent the ridge tile 32, these tiles being indicated by the reference numeral 44.

In cooler climates, where ventilation of the air space under the roof is less important, the ridge tiles 32 may be seated directly upon adjacent tiers of tiles 16, or 16a, without provision of the special flanges 42.

For relatively high pitched roofs, the tiles assembled as described therein are water-tight and additional means for sealing the tiles is not required. The configuration of the individual tiles and the manner of overlapping is such as to provide a water drainage down the sloped sides of the roof with no tendency of the water to penetrate between the tiles. For low pitched roofs where normal winds may drive the water between the overlapping tiles, the use of a suitable sealing means between tiles is recommended.

It is contemplated that the roof tiles 16, or 16a may be cast in any desirable color, and that tiles of

several colors may be combined on the same roof structure. Preferably, in tropical climates, the tiles would present a white or other highly reflective external surface to reduce heat absorption. Suitable insulation may be provided under the roof tiles as may be deemed desirable.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claim.

Having thus described my invention, I claim:

A roof construction comprising, in combination, a plurality of parallel equispaced inclined rafters, a plurality of parallel equispaced purlins engaging said rafters and extending normal thereto, said rafters and said purlins cooperating to provide a rectangular planar lattice for receiving a roof covering, a plurality of like roof tiles, there being one roof tile supported by each rafter at a point midway between each pair of adjacent purlins and one roof tile supported by each purlin at a point midway between each pair of adjacent rafters, said roof tiles having a length slightly greater than the distance between adjacent rafters and a width slightly greater than one half the distance between adjacent purlins whereby said tiles are disposed upon the rectangular lattice of purlins and rafters in equispaced tiers extending parallel to said purlins, the tiles in adjacent tiers overlapping in staggered relationship and adjacent tiles in each tier overlapping, each said tile having four spaced right angular flanges projecting normally from the underside thereof arranged to form two intersecting channels in the nature of an open cross engageable with the lattice thereunder, and means for securing the flanges to the lattice.
